DOOR LOCK

Arthur W. Thomas, Los Angeles, Calif.

Application January 11, 1949, Serial No. 70,156

2 Claims. (Cl. 292—337)

1

This invention relates to door locks, and particularly to improvements in door latching devices of the type disclosed in my Patent No. 2,491,783 dated December 20, 1949.

One object of my invention is to provide a door lock which is adjustable in width to adapt it to be readily applied to use on doors of various widths, said lock employing adjusting screws of special form which, in addition to drawing opposite sides of the lock toward each other to clamp the same in place on the door, serve to retain the parts in operative position to prevent relative rotation of the lock elements.

Another object is to provide a door lock which embodies a latch-bolt unit mounted in an opening in an edge of the door, and latch-bolt operating means which comprises a housing disposed in a transverse opening of the door and including a slidably operating member operatively connected to the latch-bolt to slide the same, said housing having a flange engageable against one side of the door, the lock also having manually operable knobs at each side of the door and spindles connected to the knobs and adapted, when rotated, to slide the operating member; the lock further including an annular plate surrounding one of the knob spindles and provided with curved bayonet slots for receiving the adjusting screws, tightening of the screws causing the plate and housing to be drawn toward each other to retain the lock on the door. It is a related object to provide an escutcheon plate for concealing the annular clamping plate and adjusting screws, said escutcheon plate encircling the knob spindle and being composed of a pair of concentric rings, the outer ring being detachably connected to the clamping plate and being movable transversely of the inner ring so as to reduce the radial dimension of the escutcheon plate at one side, so as to provide clearance for permitting engagement and rotation of the adjusting screws by a screw-driver extending generally axially with respect to the knob spindle.

Another object is to provide a door lock which includes separate knob-actuated means for sliding the latch-bolt operating member to retract the latch-bolt, and a key-actuated means also operative to slide the operating member, the lock also embodying a novel means for locking the outer knob-actuated means, and manually controlled means on the inner knob-actuated means for operating the locking means while permitting operation of the key-actuated means.

Another object is to provide a door lock which includes roller means by which the latch-bolt

2

operating member is freely mounted for easy sliding movement within the housing, the rollers being tapered and engaging inclined runners on the operating member, so that the latter is retained in its path of movement without the use of elements which might cause frictional resistance to the sliding movement of the member.

A further object is to provide a door lock which is relatively simple in construction and durable in use, and one which is highly efficient in performing its intended function.

Further objects will be set forth in the following specification, which describes a preferred embodiment of the invention, by way of example, as illustrated by the accompanying drawing. In the drawing:

Fig. 1 is a horizontal sectional view through an edge of a door, showing my improved lock applied to use therewith;

Fig. 2 is a cross-sectional view, taken on line 2—2 of Fig. 1;

Fig. 3 is a cross-sectional view, taken on line 3—3 of Fig. 1;

Fig. 4 is a sectional view, taken on line 4—4 of Fig. 2; and,

Fig. 5 is a sectional view, taken on line 5—5 of Fig. 4.

Referring to the drawing in detail, the latching and locking device is shown as applied to a hinged door 10, the free vertical edge only of which is shown. Since the present device is similar to that disclosed in my pending application referred to previously, the present description will be confined largely to the improvements outlined in the preamble of this application, and reference is made to the pending application for a more detailed description of the general structure.

The latching and locking device includes a latching unit 11 which comprises a latch 12 slidable axially in a tubular bearing 13 disposed in an opening 14 extending inwardly from the edge of the door 10. A coil spring 15 compressed between a cross-element 16 and the latch 12 normally acts to propel the latter outwardly to cause it to project into a keeper (not shown), when the door is swung to closed position, the outward movement of the latch being limited by the engagement of a shoulder 17 thereon with a flange 18 on the tubular bearing 13.

Disposed in a transverse opening 19 of the door 10 is a cup-shaped housing 20 which has a peripheral flange 21 at its open end adapted to seat against the outer side of the door. The inner end and that portion of the periphery of the

housing 20, which is adjacent the latch-bolt unit 11, are provided with connected openings 22 and 23, respectively. An annular clamping plate 25 is disposed against the inner side of the door with its peripheral portion engaging the door adjacent the edge of the opening 19. A pair of attaching screws 26 having tapered heads 27 are adapted to be screwed into tapped holes in the end wall of the housing 20, the screws passing through curved bayonet openings 28 in the clamping plate (Fig. 5). The openings 28 have enlarged portions 29 at one end to adapt the plate 25 to be placed over the heads of the screws 26, the plate then being turned to cause the screws 26 to be positioned at the opposite ends 30 of the openings. As shown in Fig. 4, the metal surrounding the ends 30 is depressed to provide, in effect, sockets in which the tapered portions of the screw heads 27 are adapted to seat. By tightening the screws 26, the housing 20 is drawn toward the clamping plate 25, and thus retained in place in the door.

A frame member 33 is disposed within the housing 20 and is retained therein by virtue of the engagement of its ends with the inner surface of the housing and a screw 34 (Figs. 1 and 2). The frame member 33 is substantially channel-shape in cross-section, and its upper and lower flanges have openings at the ends of which are vertical ears 35. Extending between each pair of ears is a pin 36 on which is rotatable a tapered roller 37. A similar but smaller roller 38 is rotatable between the vertical sides of the frame member 33, said roller being arranged on the horizontal center line of the housing 20.

A latch-bolt operating member 40 is disposed within the housing 20 and adapted to slide transversely thereof. The member 40 is substantially fork-shaped, being provided with upper and lower horizontal legs 41 which are connected by a vertical strip 42 (Fig. 2). As shown in Fig. 4, the legs 41 have bent inclined portions or runners 43 which engage the peripheries of the rollers 37 to adapt the member 40 to move laterally toward and away from the edge of the door 10. The metal of the legs 41 of the operating member 40 is bent laterally to provide a pair of centrally located inclined runners 44 which embrace the third roller 38. It will be apparent, by referring to Fig. 4, that the rollers 37 and 38, in addition to providing mounting means for the operating member 40, also co-operate with the inclined runners 43 and 44 in maintaining the member in position against the inner face of the frame member 33, and this is a feature of the present invention, it being noted that the operating member is retained without the use of separate bent portions of the frame, so that friction is reduced to a minimum and free movement of the member in the housing is assured. The operating member 40 is provided with a bent finger 45 which is engageable in a slit of the latch-bolt 12.

Brazed or otherwise attached to and extending vertically between the runners 43 is a generally curved element 48 which has a central U-shaped portion 49. A pair of coil springs 50 compressed between the element 48 and lugs on the frame member 33 act to urge the operating member 40 toward the edge of the door so as to project the latch-bolt 12 outwardly. The operating member 20 is, however, adapted to be moved in the opposite direction, against the action of the springs 50 by means to be next described.

The clamping plate 25, previously described, carries a tubular shell 55 in which is rotatable a tubular spindle 56 having an inner knob 57 secured to its outer end and by which the spindle 56 can be rotated. The inner end of the spindle 56 has an arcuate actuator 58, either edge of which is adapted to engage the curved portion of the element 48, depending upon which direction the spindle is turned by the knob, whereby to force the operating member 40 toward the right, as indicated by the broken lines in Fig. 2, so as to retract the latch 12. A lock-actuator element 60, in the form of a slender rod, is slideable axially in the spindle 56 and extends through the housing 20, as shown in Fig. 1, the end of the rod having an enlargement 61. The actuator rod 60 is connected to a tubular finger-piece 62 which is normally projected from the knob 57 by a spring 63. The finger-piece 62 has a shoulder 64 which, when the finger-piece is pressed inwardly and turned, engages a fixed lug 65 within the shell 55 so as to retain the same in this position.

Slidably mounted on the tubular shell 55 and the hub of the knob 57 is a frusto-conical ring 68. Surrounding the ring 68 is a second similarly shaped ring 69, the two rings together providing an escutcheon plate 70. The purpose of this two-part construction will be apparent by referring to Fig. 4, wherein it will be seen that by drawing the escutcheon plate outwardly along the shell 55, the outer ring 69 can be lowered with respect to the inner ring 68 so as to provide clearance for a screw-driver 71, when the latter is employed for tightening or loosening the attaching screws 26, and this is also a feature of the present invention.

The operating member 40 is also adapted to be moved to retracted position by an outer manually-operable means 75, which includes a circular plate 76 having an axial tubular shell 77 secured thereto. The plate 76 is attached to the peripheral flange 21 of the housing 20 by screws 78, and is provided with a notch 79 at the intersection of the inner portion of the plate and the shell 77. Rotatable in the shell 77 is a tubular spindle 80 which carries the outer knob 81, this spindle having an arcuate actuator portion 82 disposed within the housing 20 and adapted, when rotated in clockwise direction (Fig. 3), to force the operating member 40 toward the right (Fig. 2) so as to retract the latch-bolt 12, the spindle 80 carrying the tumbler housing of a tumbler lock 87. Rotatable within the spindle 80 is a smaller tubular spindle 85, which also has an arcuate actuator portion 86 adapted, when this spindle is rotated in counterclockwise direction (Fig. 3), to retract the operating member 40 and latch-bolt 12. The outer end of the spindle 85 carries the rotatable cylinder of the tumbler-type lock 87 into which a key (not shown) is insertable to rotate the spindle. Since the lock 87 may be of any conventional type, it is not herein shown or described in detail. A circular escutcheon plate 88 on the shell 77 serves to shield the plate 76.

It is apparent from the foregoing that the operating member 40 can be retracted by rotating any of the spindles 56, 80, or 85. The spindle 85 is normally locked, by means of the lock 87, to the spindle 80 so that rotation of the outer knob 81 effects simultaneous rotation of the two actuators 82 and 86. However, means are provided for preventing rotation of the knob 81 and its spindle 80 when the finger-piece 62 is locked in depressed position. This means consists of a

tubular locking member 90 which is slidable axially in a tubular bearing 91 formed integral with a plate 92 secured to the side of the frame member 33 (Fig. 1). The locking member 90 has a reduced bore 93 at its inner end through which the tip of the lock-actuator rod 60 passes. The member 90 has a radial arm 95 of a width adapted to enter the notch 79 of the plate 76, and an aligned notch 96 in the inner end of the spindle 80. Closing the outer end of the bearing 91 is a thimble 97, and compressed between this thimble and the locking member 90 is a spring 98 which forces the member inwardly to normally displace the locking arm 95 from the aligned notches 79 and 96. When the lock-actuator rod 60 is forced inwardly, however, the enlargement 61 thereof engages the inner end of the locking member 90, to force the arm into the notches 79 and 96 so as to prevent rotation of the spindle 80 and retain the latch-bolt 12 in outer locked position. The latch-bolt 12 may, however, be retracted by rotating the spindle 85 by inserting an appropriate key in the tumbler lock 87 and turning the same, it being apparent from Fig. 1 that the inner end of the spindle 85, which is disposed adjacent the arm 95, terminates short of the notches 79 and 96. The improved locking elements 60, 90, 79, 96, together provide a simple and positive means for locking the outer spindle 80 against rotation and is an important feature of the present invention.

It is thus seen that the present invention provides several improvements in door lock structures of the general type shown in my pending application, referred to herein, these improvements providing greater ease of movement of the latch-bolt operating elements and a more positive means for locking the outer spindle against actuation, besides providing greater facility in installing the locking device on the door.

The improvements disclosed herein are susceptible of various modifications which would fall within the spirit of the invention. Consequently I do not wish to be limited in this respect, but desire to be afforded the full scope of the following claims.

I claim:

1. In a lock structure adapted for use on a door and including a latch-bolt unit insertable in an opening in an edge of the door, said unit having a slidable latch-bolt, the combination of: a housing insertable in a transverse opening in the door; tapered rollers within said housing; an operating member having inclined longitudinal runners engageable with and movable along said rollers, the inclination of said runners corresponding with the taper of said rollers so that said rollers retain said operating member within its plane of sliding movement; and manually operable means for sliding said operating means.
2. In a lock structure adapted for use on a door and including a latch-bolt unit insertable in an opening in an edge of the door, said unit having a slidable latch-bolt, the combination of: a housing insertable in a transverse opening in the door; tapered rollers rotatable in said housing; an operating member having inclined longitudinal runners engageable with and movable along said rollers, said runners and rollers cooperating in maintaining said operating member against an inner surface of said housing; and manually operable means for sliding said operating member.

ARTHUR W. THOMAS.
